HENRY B. COOLEY, OF KENSINGTON, CONNECTICUT, ASSIGNOR TO THE AMERICAN PAPER GOODS COMPANY, OF MONTCLAIR, NEW JERSEY, A CORPORATION OF NEW JERSEY.

FEEDING MECHANISM FOR FASTENER-SETTING MACHINES.

1,294,772.

Specification of Letters Patent. Patented Feb. 18, 1919.

Application filed May 18, 1916. Serial No. 98,306.

To all whom it may concern:

Be it known that I, HENRY B. COOLEY, a citizen of the United States, and a resident of Kensington, in the county of Hartford, 5 and State of Connecticut, have invented a new and Improved Feeding Mechanism for Fastener-Setting Machines, of which the following is a specification.

My invention relates more especially to machines for affixing fastening devices to envelopes and by means of which the envelopes are temporarily secured to close the openings to the flaps, and an object of my invention, among others, is to provide a machine of this class that shall be simple in construction and in its method of operation and particularly efficient as to the character of work performed thereby.

One form of machine embodying my invention and in the construction and use of which the objects herein set out, as well as others, may be attained, is illustrated in the accompanying drawings, in which—

Figure 1 is a view in front elevation of 25 a portion of a machine embodying my invention with parts broken away to show construction.

Fig. 2 is a detail view, scale enlarged, partly in section, showing the construction 30 of the plunger slides.

Fig. 3 is a detail view, scale enlarged, in vertical section of a portion of my improved machine showing the riveting feeding mechanism, the view being from the 35 back of the machine.

Fig. 4 is a similar view but looking toward the right hand side of the machine, this view being on plane denoted by dotted lines 4—4 of Fig. 2.

Fig. 5 is a top plan view of a portion of 40 my improved machine showing the rivet feeding mechanism.

Fig. 6 is a detail view illustrating the construction and operation of the aliner.

Fig. 7 is a detail view looking toward the 45 face of the chute for the rivets.

Fig. 8 is a detail side view of the upper part of the chute and lower part of the rivet guide.

50 The invention forming the subject matter of this application relates to the machine illustrated and described in my copending application of Serial Number 746,798 filed February 7th, 1913, the present

invention relating to the riveting mechanism of said machine, and for this reason part of the mechanism of said machine not constituting a direct part of said riveting mechanism is omitted from the drawings herein and reference is hereby made to the 60 patent to be issued on said copending application for a disclosure of such parts of the machine as are not shown herein.

In the accompanying drawings the 65 numeral 10 denotes legs supporting a bed 11 of the machine, which parts are of any suitable material secured together in any desired manner. A driving pulley 12 supported on a driving shaft at the rear of the machine is adapted to receive a belt 70 driven from any suitable source of power and the pulley may have any desired mechanism for securing it in or detaching it from driving connection with the shaft, the mechanism for operating this connection including a starting and stopping pin 13, and an operating lever 14 pivotally supported by the bed on a bar projecting therefrom and pivotally connected at one end with said starting and stopping pin and at its other 75 end with an actuating rod 15 connected with a treadle 16 arranged to be actuated by the feet of the operator of the machine, a spring 17 secured at its upper end to the rod and at its lower end to the treadle pulling the 80 rod normally downward and causing the pin 13 to be normally held in position to disengage said pulley from the driving shaft, and as more particularly shown in my said copending application. When the 85 treadle is pressed downward upward movement of the rod 15 moves the pin 13 downward into position to permit operation of the parts to connect the pulley with the driving shaft. The driving shaft is connected in any suitable manner at its opposite ends to rotate cross shafts 18 and 19 mounted in bearings on the bed 11. A supporting slide 20 is mounted for reciprocating movement in a slideway 21 in the bed 100 11, the slide being held in place in any suitable manner as by dove-tailed projections 25 engaging similarly shaped grooves 26 in the slideway. This slide has a supporting plunger 22 rigidly secured thereto at one 105 side and a cap 23 secured to the slide has an actuating rod 24 pivotally attached to the cap and connected with an eccentric 27 se-

75

cured to the shaft 18, that are employed to reciprocate the slide.

A riveting slide 28 is mounted in a slide-way 29 formed in the bed on the opposite side of the center thereof from the slideway 21, this slide being held in place in a manner similar to that above described with respect to the slide 20. A riveting plunger 30 is secured to the slide 28 and this plunger 10 has a centrally located recess in which a rivet punch 31 is removably secured, projecting beyond the end of the plunger 30. This punch is tubular and contains a rivet supporting pin 32 having a head 33 to retain it in place, a spring 34 being located in the recess behind said pin and thrusting against it to force it normally outward.

A cap 35 secured to the riveting slide 28 has a slide actuating rod 36 pivotally secured thereto, said rod being connected with an eccentric 37 secured to the cross shaft 19, by means of which eccentric the slide 28 is reciprocated. An adjusting screw 38 is mounted in the cap 35 and serves as a back-stop to properly locate the plunger 30. A rest 39 is located in an envelop receiving opening 40 in the bed of the machine upon which rest the envelops are placed on edge, and a supporting shoe 41 is secured at one 30 end to a block 42 located in the slideway 29 and secured to the bed, the end of the shoe being pointed and extending along the opening 40, as clearly shown in Fig. 2, in position to project into an envelop, the end of 35 the flap of which rests against an envelop stop 43 to be hereinafter described. A die 44 against which the rivets are held by the punch 31 is secured to the shoe and an envelop guide 45, in the form of a spring, is secured at one end to the shoe and projects to guide the envelop over the die 44 when the former is placed on the shoe, the guide yielding and its free end moving toward the shoe when the riveting takes place.

45 A supporting bar 46 is secured to the legs 10 at the front of the machine and extends thereacross from side to side, a rest support 47 projecting upwardly from said bar at about its center and having the envelop 50 stop 43 that is adjustably supported on the bed 11, located over or resting against its upper end. A dove-tailed shaped rest guide 48 is secured to the rest support, the end of the rest 39 having a dove-tailed shaped 55 groove to engage said guide as shown in Fig. 2 of the drawings, this groove extending into a base 49 of the rest, which base is provided with a set screw (see Fig. 1) by means of which the rest may be detachably secured in any desired position.

A post 50 rises from the bed 11, this post being curved forwardly at its upper end to locate a holder disk 51 rotatably supported at its upper end over a rivet feed for sup-

plying rivets to the mechanism. A holder 52 is secured to the disk 51, this holder being in the form of a wire upon which the rivets 53 are placed, these rivets being of a form commonly used on envelops and each having a central tubular portion 54 with flexible arms 55, as shown in Fig. 4, which arms are adapted to be passed through an opening in the flap of an envelop and then bent backwardly to hold the flap of the envelop in place. A guide 56 of trough shape to receive the rivet arms on one side of the tubular portions of the rivets located on the holder 52, is secured to or forms part of the cover for a rivet chute hereinafter described. The disk 51 may be rotated as by means of a handle 57 to place the holder in a position diametrically opposite to that shown in Fig. 1, in which position the holder may be "loaded" and after which, and before it is placed in position to feed an aliner 58, 20 pivotally mounted on one side of the post 50, is employed, when swung into an upward position (see Fig. 6), to aline the rivet arms so that they will be properly located in the guide 56 when the holder is 25 rotated to the feed position shown in Fig. 1. When not in use to aline rivets the aliner may be swung downwardly against the back of one of the flanges on the post 50. This aliner consists of an arm having a groove to 30 receive the arms of the rivets, which aliner arm is pivotally mounted on the post, as clearly shown in Fig. 6, it being of a length to engage all of the rivets on the holder when swung upwardly from its position of 35 rest which is a position at right angles to the position shown in Fig. 6.

A bracket 59 is secured to the front of the bed, rising therefrom to support a rivet feed wheel 60 rotatably supported in 40 branches 61. This feed wheel has feed pins 62 projecting therefrom and a ratchet 63 is secured to the shaft of said wheel, preferably underneath the branches to rotate it. A pawl arm 64 is rotatably mounted on the 45 shaft of said feed wheel and bears a pawl 65 adapted to engage the teeth of the ratchet. A ratchet rotating bar 66 is adjustably secured to a support 67 rising from the rivet slide 28, the ratchet being thus operated at 50 each reciprocating movement of said slide.

A chute 68 is secured to the block 42, rising upwardly therefrom and curved to underlie the lower end of the guide 56. This chute has a groove 69 which is closed 55 by a cover 70 secured to the side parts of the chute, in the construction herein shown the guide 56 being secured to the chute above the cover. The feed wheel 60 projects through one side of the groove 69, the flexible 60 arms of the rivets 55 resting upon a side part at the upper end of the chute 68 and upon the feed wheel. In each reciprocating

movement of the slide 28 the feed wheel is given a one step rotation, causing a pin thereon to strike an arm of the lower-most rivet, imparting to the rivet a quarter turn 5 and alining the arms with the groove 69 in the chute. As soon as the arms are thus alined the lowermost rivet drops onto the inclined bottom of the groove and falls to a position in front of a hole 71 in the chute 10 68 in which position it is held by a rivet rest 72 in position to receive the rivet punch 31.

The lower part of the runway or groove 69 is closed by a gate 73 mounted on a latch 15 74 pivotally supported on the bracket 42 and having a cam 75 located in the path of movement of the end of the plunger 30. This gate has an opening 77 in its edge to receive the hollow hub of the rivets, and 20 the cam 75 is so formed that as the riveting plunger 30 moves forward it operates to move the gate backward at the proper time from in front of the rivet that is thus allowed to be carried by the pin 32 against 25 the die 44, a spring 76 returning the latch to its normal position as shown in Fig. 4, this spring being attached to a pin 78 on the latch.

The lower end of the guide 56 is offset to 30 form a separating slot 80 between this offset portion and the upper edge of the chute 68 as clearly shown in Fig. 3 of the drawings. As the rivet is turned from the position shown in Fig. 4, by the wheel 60, one 35 arm of the rivet passes into the separating slot and the rivet, when the wheel 60 has alined it with the groove 69, separates from the stack and falls onto the sloping surface of said groove, and into the position as 40 shown in dotted lines in Fig. 3 of the drawings.

While I have shown and described herein in a machine, the construction of which satisfactorily embodies my invention, this may 45 be departed from to a greater or lesser degree and yet be within the spirit and intent of the invention.

I claim—

1. A rivet feed device including a holder 50 to receive tubular rivets, a rotatable member to which said holder is secured and located normally in a position to cause vertical feed of rivets in succession from said holder, a rest to receive a rivet therefrom 55 and to permit its movement between the rest and the end of the holder, and means for feeding rivets from said rest,

2. A rivet feed device including a holder 60 to receive tubular rivets, a rotatable member to which said holder is secured, said member being movably secured in place for the holder to receive rivets in one position, means for retaining said member with the holder in another position for the successive 65 feed of rivets therefrom, a rest to receive

rivets from the holder, said rest being spaced from the holder to permit passage of rivets, and means for feeding rivets from said rest.

3. A rivet feed including a holder rotatably mounted and arranged to receive hollow rivets having laterally projecting arms thereupon, a grooved guide positioned to receive the arms of said rivets, and a feed device for removing rivets from underneath said holder. 75

4. A holder rotatably mounted to receive hollow rivets thereupon, means for rotatably positioning said holder, and a grooved aliner pivotally mounted and arranged to engage and aline hollow rivets mounted upon said holder. 80

5. A rivet feed device for rivets having arms, said device including a grooved runway, means for pivotally turning a rivet resting with its arms upon the sides of said runway so that said arms will extend along the runway, and means for operating upon said rivets and to which the rivets move along said runway. 85

6. A rivet feed device for rivets having arms, said device including a grooved runway, means for presenting rivets to said runway with their arms resting upon the sides thereof, means for turning the rivets to aline with the runway, and means for operating upon said rivets and to which the rivets move along said runway. 90

7. A rivet feed device for rivets having arms, said device including a grooved runway having a part arranged in an inclined position, means for presenting rivets with their arms resting upon the sides of the runway over said inclined portion, means for turning the rivets to aline with said runway, and means for operating upon said rivets and to which the rivets move along said runway. 100

8. A rivet feed device including a grooved runway, a feed wheel, means upon said wheel to engage rivets and to turn them upon their own axes for feed along said runway, means for operating the wheel, and means for operating upon said rivets and to which the rivets move along said runway. 110

9. A rivet feed device including a grooved runway, a feed wheel supported in co-operative relation with said runway, pins projecting from said wheel to engage rivets and to turn them upon their own axes for feed along the runway, means for operating the wheel, and means for operating upon said rivets and to which the rivets move along said runway. 115

10. A rivet feed device including a grooved runway, a feed wheel with its periphery located in a recess in one side of said runway, means for supplying armed rivets each with one arm resting upon the side of the runway, and the other upon said wheel, means for rotating the wheel to turn the rivets to 120 125 130

- aline with said runway, and means for operating upon said rivets and to which the rivets move along said runway.
11. A rivet feed device including a grooved runway, a feed wheel having its periphery located in a recess in one side of said runway, pins upstanding from said wheel, means for supplying armed rivets each with one arm resting upon a side of the runway and the other arm upon said runway between said pins, means for rotating the wheel, and means for operating upon said rivets and to which the rivets move along said runway.
12. A rivet feed device including a rotatably mounted holder member, a holder projecting from said member to receive and discharge rivets from the same end, means for rotating the holder to a loading position and also to a feeding position, a grooved runway underlying the end of the holder when in its feeding position, means for removing rivets from the holder, and means for operating upon said rivets and to which the rivets move along said runway.
13. A support, a rivet holder movably mounted on said support, a rivet aliner movably mounted on said support to aline rivets thereon, a guide positioned to receive the holder and alined rivets, means for removing the rivets from the holder, and means for operating upon said rivets and to which the rivets move along said runway.
14. A rivet feed device including a holder movably mounted to receive hollow rivets thereon in one position, means for moving the holder from said position to a feed position, means for successively moving the rivets separately and individually from the holder while in its feeding position, and means for guiding the rivets in their movements from underneath said holder.
15. A rivet feed device including a movably mounted holder arranged to receive hollow rivets thereupon on one end, means for reversing the holder for the discharge of the rivets from said end of the holder, and means for removing the rivets from underneath the holder.
16. A rivet feed device including a holder, pivotally mounted at one end to receive hollow rivets upon its opposite end, means for reversing the position of the holder upon its pivot for the discharge of rivets therefrom, and means for removing the rivets from underneath said holder.

HENRY B. COOLEY.
